ECCENTRICALLY HINGED TRACTOR WHEEL CLEANER

Application filed September 21, 1931. Serial No. 564,236.

This invention relates to a wheel cleaner adapted to be applied to a tractor and it consists in the novel features hereinafter described and claimed.

5 The object of the invention is to provide a cleaner of the character stated, adapted to be mounted upon the gear casing of a tractor wheel, and having a blade so mounted as to bear upon the periphery of the wheel between 10 the lines of lugs which are mounted upon the wheel rim.

A further object of the invention is to provide a cleaner as stated, including a breakable part, which will fracture in the event that 15 the blade strikes an obstruction lodged between the lugs and inasmuch as the cleaner is eccentrically and pivotally mounted with relation to the wheel, the blade will pass under the said obstructing object and force 20 the same from between the lugs.

In the accompanying drawings:—

Figure 1 is a side elevational view of a tractor wheel with the cleaner applied to the gear casing thereof.

25 Figure 2 is a top plan view of the same.

Figure 3 is a rear elevational view of the same.

Figure 4 is a fragmentary sectional view cut on the line 4—4 of Figure 1.

30 Figure 5 is a similar view cut on the line 5—5 of Figure 1.

Figure 6 is a detailed fragmentary sectional view cut on the line 6—6 of Figure 1.

35 As illustrated in the accompanying drawings the tractor wheel is shown at 1. Tractor lugs 2 are mounted upon periphery of the wheel and the said lugs are arranged in rows there being a row adjacent each edge of the

40 periphery of the wheel and with a space between said rows. The usual gear casing 3 is mounted at the side of the wheel. A bracket 4 is attached to the side of the casing and an arm 5 is pivoted to the said bracket. The arm 5 is provided with an angularly disposed

end 6, and a blade 7 is carried by the end portion 6 of the arm 5 and bears at its edge upon the periphery of the wheel in the space between the two rows of lugs. A clip 8 is

45 mounted at the side of the arm 5 and a snap pin 9 of wood or other fragile material is

carried by the clip 8 and the arm 5. The pin 9 passes through the clip and the said arm, as best shown in Figure 5 of the drawings. An adjustable brace device is interposed between the snap pin 9 and the casing 3, said device consists of ear members 10, one of which is pivoted to the casing 3 and the other lying between the clip 8 and the arm 5 and surrounding the snap pin 9. A bolt 11 passes through the inner ends of the ear 60 members 10 and is provided with clamp nuts 12 which are screwed upon the bolt at the opposite sides of the inner ends of the ear members.

The adjustable brace device is provided so 65 that the blade 7 can be adjusted to or from the periphery of the wheel 1. This adjustment is to prevent blade 7 from bearing directly upon periphery of wheel and causing undue wear of periphery of wheel or 70 blade 7. This adjustment also compensates for wear of blade 7.

In operation as the wheel 1 turns in a forward direction, the blade 7 passes under any material which may have gathered between 75 the lugs 2 and force the same out from between the said lugs. In the event that a stone should lodge between the lugs, the blade 7 will enter between the stone and the periphery wheel, and as the pressure upon 80 the blade and the arm increases, the pin 9 will break and the arm 5 is swung in an upward direction whereby the blade 7 passes from under the stone. This is due to the fact that the arm 5 is eccentrically mounted with 85 relation to the wheel 1. After the periphery of the wheel has been cleared, the arm 5 may be swung back, a new snap pin inserted, and the tractor may continue upon its course. The attachment prevents the soil from accumulating between the mud lugs and the periphery of the wheel causing slippage and also preventing the formation of ruts in the space of the ground.

Having described the invention, what is 90 claimed is:—

A tractor wheel cleaner comprising a bracket having a support, an arm pivoted to the bracket, a blade carried by the arm and adapted to bear upon the periphery of the 100

wheel, a snap pin mounted upon the arm and an extensible connection mounted upon the snap pin and adapted to be connected with the bracket support.

5 In testimony whereof we affix our signatures.

CHARLES R. MEYER.
FLOYD W. COX.
